(74) Attorney, Agent, or Firm—Rick Martin; Patent Law Offices of Rick Martin, P.C.

(57) **CLAIM**

The ornamental design for a paw shaped bottle opener, as shown and described.

DESCRIPTION

FIG. 1 is a plan view of the top side and bottom sides, which are mirror images of each other, of my new design for a paw shaped bottle opener.

FIG. 2 is a right side elevation view of FIG. 1.

FIG. 3 is a left side elevation view of FIG. 1.

FIG. 4 is a front side elevation view of FIG. 1.

FIG. 5 is a rear side elevation view of FIG. 1; and, FIG. 6 is a top perspective view of FIG. 1.
